ASH TRAY

Charles Webke, Weehawken, N.J.

Application March 13, 1959, Serial No. 54,981

Term of patent 14 years

(Cl. D85—2)

I claim:

The ornamental design for an ash tray, as shown.
